UNITED STATES PATENT OFFICE.

SAMUEL F. MERRITT, OF SPRINGFIELD, MASSACHUSETTS.

EYEGLASS-HOLDER.

SPECIFICATION forming part of Letters Patent No. 248,600, dated October 25, 1881.

Application filed June 18, 1881. (No model.)

To all whom it may concern:

Be it known that I, SAMUEL F. MERRITT, a citizen of the United States, residing at Springfield, in the county of Hampden and State of Massachusetts, have invented new and useful Improvements in Eyeglass-Holders, of which the following is a specification.

This invention relates to the details of improvements in the construction of eyeglass-holders, the object being to so improve the construction of such devices as to prevent eyeglasses from becoming accidentally unhooked therefrom, and to simplify and reduce the number of parts heretofore required in this class of articles.

In the drawings forming part of this specification, Figure 1 is a perspective view of an eyeglass-holder constructed according to my invention. Fig. 2 is a view of the latch detached from the holder. Fig. 3 is a rear view of the main portion of the body of the holder. Fig. 4 is a vertical section. In the drawings the parts are all shown much enlarged for the purpose of clearer illustration.

25 In the drawings, *a* is the body of the eyeglass-holder. *c* is the latch. *e* is the hook-catch. *i* is a spring cut from and integral with the body *a*, and *v* is the pin.

The eyeglass-holder herein described is composed of three separate pieces only—viz., the body, the latch, and the hook-catch.

The body *a* is cut from a sheet of metal. Its front hook portion, *b*, has the corrugation *x* formed through its center. The end of part *b* each side of said corrugation is cut away, as shown, to let the end of the latter project above the sides thereof, forming a point, *z*. The spring *i* is formed by partially separating a portion of the body *a* from itself, and by bending the upper end of said partially-separated portion forward, so that it projects beyond the front face of said body, as shown. The ears *n n* on body *a* are perforated to receive the ends of the trunnions *s s* on the latch *c*. The sharpened pin *v* is properly rounded and finished, and bent rearwardly and down, as shown, and the front part, *b*, is bent up to the position shown in Figs. 1 and 4, and the pin-catch *e*, consisting of the ordinary broken ring with a shank on it, is thereby riveted into body *a* just above the lower end of the pin *v*.

The latch *c* is cut from a sheet of metal, and has its trunnions *s s* rounded, its lower point half-rounded on its upper side, and its ears *r r* turned up to a vertical position, and when

thus prepared the ears *n n* on body *a* are turned up, and said trunnions *s s* being placed in the perforations therein, said ears *n n* are bent up to the position shown, thereby securing said latch to the body *a* directly over the forwardly-bent end of spring *i*, which bears against the under side of said latch and forces it against the end *z* of the corrugation on the front part, *b*, and carries the half-rounded lower point of said latch into the corrugated groove under the end of said part *b*, while the point *z* lies upon the face of said latch, having its end slightly curved upward, and reaches up between the ears *r r* on said latch. The half-rounded point *z* on the latch *c* lies in the corrugated groove *x* at the upper end of the part *b*, and thereby aids in preventing lateral movement in that end of said latch.

The eyeglass-holder constructed as above described and shown, and having its eyeglass-hook *b* provided with the corrugation *x*, is very strong and rigid. The position of and the manner in which spring *i* operates render it impossible for the eyeglass itself to so disengage it from the latch *c* as to allow the latter to swing away from the end of the part *b* and let the eyeglass escape therefrom. The eyeglass is placed on hook *b* by pressing the ring thereof upon the latch *c* just above the ears *r r*, when said latch will be depressed, allowing said ring to pass freely between the point *z* on the eyeglass hook *b* and the end *z* on the latch *c*, when the latter, actuated by spring *i*, will close up, as seen in Fig. 1. To remove the eyeglass from its hook, one bears down upon the ears *r r* on latch *c* to open it away from the end of hook *b*.

The eyeglass-holder is secured upon the garment of the wearer by the pointed pin *v* and the catch *e* in the usual manner.

What I claim as my invention is—

1. The within-described eyeglass-holder, consisting of the body *a*, provided with the pin *v*, and having the hook *b* and the spring *i* formed integral with said body, and the latch *c* pivoted thereto, substantially as set forth.

2. The combination, in an eyeglass-holder, of the body *a*, having the pin *v*, the hook *b*, the spring *i*, and the ears *n n*, formed integral with said body, and of the latch *c*, substantially as set forth.

SAMUEL F. MERRITT.
